UNITED STATES PATENT OFFICE.

CRAIG R. ARNOLD, OF PHILADELPHIA, PENNSYLVANIA.

STEAM-ENGINE.

SPECIFICATION forming part of Letters Patent No. 364,627, dated June 14, 1887.

Application filed August 30, 1886. Serial No. 212,170. (No model.)

To all whom it may concern:

Be it known that I, CRAIG R. ARNOLD, a citizen of the United States, and a resident of Philadelphia, in the State of Pennsylvania, 5 have invented certain new and useful Steam-Engines, of which the following is a specification.

My invention relates to steam-engines of that class wherein two or more cylinders, communicating with a common steam-chest, are located upon and open into a crank case or vat, within which the operative parts revolve in a lubricating bath.

The object of my invention is to render this 15 type of machine, as far as possible, automatic in its operation, and to reduce to a minimum the labor of superintendence. This object I attain, generally speaking, by reducing the wear upon the bearing-surfaces and by making 20 the arrangements for lubricating the working parts of the engine completely automatic in their operation.

My invention consists in providing each of the cylinders with a steam-cushion chamber 25 to take up the pressure of the descending piston, so as to relieve the bearings of the crank-shaft from the pounding and wear incident to the ordinary operation of the piston.

It also consists in jointing the connecting- 30 rod to the piston and to the crank respectively, so as to make the line of motion of the connecting-rod on the downward or working stroke as nearly as possible perpendicular to the crank at the point of greatest thrust—that is to say, 35 when the crank is in its extreme horizontal position.

It also consists in inclining the upper face of the piston-head so as to relieve the tendency 40 of the piston to hang or buckle, due to the eccentric jointing of the connecting-rod.

It also consists in providing the engine with a hollow connecting-rod and suitable devices to force the lubricating material up through such connecting-rod to the wrist-pin for the 45 purpose of lubricating the same.

It also consists in an automatic float whereby the lubricating fluid in the vat is maintained at a constant level.

It also consists in carrying the steam-chest 50 somewhat above the top of the cylinders in order to secure the steam-ports to the two cylinders of equal length.

It also consists in providing self-adjusting bearings for the crank-shaft, whereby said shaft may be easily lined up without resorting 55 to the ordinary methods.

It further consists in certain details of construction more particularly described herein, and pointed out in the claims.

In the accompanying drawings, Figure 1 is 60 a longitudinal vertical central section showing parts in elevation. Fig. 2 is a transverse vertical section through one of the cylinders and connecting-rod. Fig. 3 is a diagrammatic representation of the connecting-rod in its various positions. Fig. 4 is a detail view of one of the features of my invention. Fig. 5 is a transverse vertical section showing the float in elevation with other parts of the machine removed. Fig. 6 is a horizontal section on the 70 line *xx*, Fig. 1.

A and B are cylinders located upon the crank-case C, with their lower ends open thereto. The connecting-rods *a b* are joined at one end to the pistons E F, and at the other 75 end to the cranks G H, oppositely placed upon the crank-shaft I—that is to say, making an angle of one hundred and eighty degrees with each other.

The steam-chest L, located between the cylinders and rising some distance above the same, is provided with the ordinary ports leading into and out of said cylinders. By carrying the steam-chest some distance above the cylinders, I am enabled to make the steam- 85 ports *c d* symmetrical in their relation to the cylinders and of equal length, as shown.

The main or distribution valve V is reciprocated in the steam-chest by means of the pitman *v* and the eccentric *W*, in the ordinary 90 manner. The steam admitted to the steam-chest by the live-steam ports 21 or 22, either of which may be suitably connected to the source of supply, as may be convenient, enters the cylinders through the passages *c* and *d* 95 when the pistons are in their upward position. When the pistons have finished their downward stroke, the steam is exhausted through the same ports, and is led through suitable passages in the main valve to the exhaust-chamber T. The exhaust-chamber communicates with an annular chamber, *h'*, surrounding the steam-chest, by means of the ports 100 9 10. The cylinders A B are also cored out to

form the annular chambers 11 12, communicating with the annular chamber h' , surrounding the steam-chest. By means of this construction the exhaust-steam is permitted to circulate around the steam-chest and the cylinders, thereby serving to steam-jacket these parts and maintain the temperature of the same, and at the same time to reduce the temperature of the exhaust-steam. The exhaust-steam escapes from the annular chamber h' through the exhaust-ports 23 or 24, either of which may be utilized for that purpose, as may be convenient. The steam-chest is closed in at some point below the ports 9 10 by the stationary head 14, forming a close joint with the shoulder 15, which supports the gland-bearing 16. The gland-bearing makes a steam-tight joint with the pitman in the usual manner.

It will be apparent that by replacing the auxiliary or moving piston, which is ordinarily employed in this class of machines, by the stationary head, as described, the working-parts will be relieved of the pounding or hammering due to the irregular action of the exhaust-steam upon the auxiliary piston, tending as it does to accelerate its downward movement and to retard its upward movement.

My device for cushioning the piston on its downward or working stroke is as follows: The pistons and cylinders are made differential in diameter. The piston-head c fits and slides in the enlarged portion of the cylinder f , and the piston-slide g fits and slides in the reduced portion of the cylinder h h' , thereby forming an annular chamber, L , around the piston-slide and beneath the piston-head.

Ports M M' lead through the cylinder-walls from the exhaust-chamber of the steam chest and open into the annular chamber L in such position as to just clear the top of the piston when it is at the limit of its downward travel.

The operation of this part of my machine is as follows: In the position shown in Fig. 1 the piston E has completed its downward stroke and the piston F is in position to begin its downward stroke. The steam being admitted through the port R' , the piston F is forced to the bottom of the cylinder, thereby forcing up the piston E into its initial position, and any water of condensation that may have found its way into the cylinder F escapes through the port m' . As the piston E rises the exhaust-steam is drawn through the port M into the annular chamber L' . Upon the downward stroke of the piston the piston-head closes the port M , and the steam left in the annular chamber is compressed by the piston-head upon its further descent and forms a steam-cushion, which takes up the pressure of the descending piston and communicates it to the frame of the engine. The operation is repeated with each of the cylinders in the same manner. A pop-valve, 25, located in the ports M M' , allows the steam to escape from the annular chamber L' when it has reached a predetermined pressure. I also relieve the wear upon the bearings of the crank-shaft, and at the

same time increase the efficiency of the machine, by the peculiar arrangement of the piston, connecting-rod, and crank, which I will now describe.

The connecting-rods a b are jointed to the crank-pin of the crank in the ordinary manner, as shown. At the other end, however, they are jointed to the piston eccentrically, the 75 wrist-pin n being located to one side of the center of the piston, and as nearly as possible in line with the crank-pin n' when the latter is at its extreme horizontal position. This is the position of the crank when the force of the 80 descending piston is most advantageously applied; and by locating the wrist-pin directly over the crank-pin I am enabled to increase this advantage by applying the downward motion of the piston in a nearly vertical direction 85 upon the crank, so that very little of the downward force is expended upon the bearings. The wrist-pin is located sufficiently far, however, from the side of the cylinder, so that it will not be necessary to enlarge the lower open 90 end of the cylinder to permit of the necessary movements of the connecting-rods.

The disadvantageous position of the connecting-rods upon the upstroke is unimportant in a single-acting machine of this description. 95 It will be seen, upon inspection of Fig. 3, that during the downward stroke, when alone work is being performed, the line of motion passing through the wrist-pin and the crank-pin is substantially vertical in all positions, and that therefore no advantage is lost from the eccentric location of the wrist-pin in any of the working positions of the engine.

To compensate for the tendency of the pistons to hang or buckle in the cylinder, due to 105 the eccentric location of the wrist-pin, I incline the upper face of the piston-head to the line of pressure in the manner shown, so as to obtain a resultant pressure in a horizontal direction.

It will be understood, of course, that the angle of inclination of the upper surface of the piston-head will depend upon the eccentricity of the wrist-pin.

The devices for automatically maintaining 115 a proper depth of lubricating fluid in the crank case or vat are as follows: A float, S , located upon the long arm of the lever s , rises and falls with the rise and fall of the liquid in the vat. To the short arm of the lever s are 120 attached the ends of the bell-crank levers r t , which control, respectively, the valve E' , which admits the water of condensation from the exhaust-chamber, and the valve E'' , which allows the water at the bottom of the mixture 125 in the vat to flow off.

The operation of the device is as follows: When from any cause the level of the mixture in the vat falls, the float S falls with it and thereby opens the valve E' , through its connection with the bell-crank lever r , thereby permitting the water of condensation from the exhaust-chamber to flow into the vat. On the other hand, when the level of the lubricating fluid rises,

the float, through its connection with the bell-crank lever *t*, opens the valve at the bottom, thereby allowing the water, which naturally sinks to the bottom of the mixture, to escape.

5 The parts are so adjusted that this action of the float will keep the liquid at the proper level.

The connecting-rods *a b* are hollow, as shown in Figs. 2 and 4, and are provided at their lower ends with openings *n*² of reduced diameter. A ball-valve, *v*, normally closes this opening. The upward travel of this ball is limited by the set-screw *w*. As the crank and the lower end of the connecting-rod dip into the lubricating-vat the commingled oil and water are forced into the lower end of the hollow connecting-rod through the aperture *n*². As the connecting-rod rises from the bath the ball-valve falls and prevents the lubricant from escaping. By a repetition of this process the lubricating fluid gradually rises in the hollow connecting-rod until it reaches the wrist-pin, which is thereby thoroughly lubricated.

25 The crank-shaft *I* is provided with tapering bearing-surfaces 11. These bearing-surfaces pass into and are automatically centered or lined up by correspondingly tapered bushings, 22. The bearing-surface proper, indicated at 2, is a lining or sleeve of Babbitt metal cast integral with the inclosing-bushing 4, and tapered on its interior surface to correspond with the taper of the shaft. The bushing 4 is screw-threaded exteriorly and screws into bracket 5. The bearings 24 are provided with a square end, 8, to which a wrench may be applied. Inclosing-caps 6, screwing into the outer end of the bracket 5, protect the parts from dust and other impurities of the air.

The operation of the devices is as follows: The wrench being applied to the square head 8 of the bearing 24, a forward and circular movement is given to the bearing-surface proper, 2, which is thereby caused not only to advance upon the tapered shaft so as to take up the wear in a longitudinal direction, but is also caused to rotate upon the same in a circular direction, thereby bringing a new surface into contact circumferentially. A set-screw, 26, passing through the bracket 5, takes into the screw-threads on the part 4 and prevents the same from moving when once adjusted.

55 A channel, 7, supplies the bearings with the lubricant from the vat. A set-screw, 26, prevents the bearings from turning with the shaft. As wear takes place the sleeve is turned by a wrench and a new bearing-surface exposed, which is caused by this arrangement to automatically center itself upon the shaft.

I am aware of the Patents Nos. 303,083 and 340,022 granted to H. H. Westinghouse, and I make no claim to the construction therein shown and described; but

What I do claim as my invention is—

1. In a single-acting engine, a cylinder hav-

ing a steam-cushion chamber alternately communicating with the steam-chest by a port which just clears the top of the piston in its 70 lowest position and closed by the piston, as and for the purpose described.

2. The combination, with a steam-chest of a single-acting engine, of a piston and a cylinder having a steam-cushion chamber formed by 75 the walls of the piston and cylinder and communicating with said steam-chest upon the up-stroke of the piston by a port which just clears the top of the piston in its lowest position, as and for the purpose described. 80

3. In a direct-acting engine, the combination of a steam-chest, a differential cylinder, a differential piston, an annular steam-cushion chamber formed thereby, and a port from said steam-chest opening into such chamber upon 85 the upstroke of said piston, as and for the purpose set forth.

4. In a single acting engine wherein the crank-shaft is in the plane of the cylinder-axis, a connecting-rod so jointed to the moving 90 parts that its line of motion upon the down or working stroke will be substantially perpendicular to the crank in its horizontal position, as and for the purpose described.

5. In a single-acting engine wherein the 95 crank-shaft is in the plane of the cylinder-axis, the combination of a piston, a crank, and a connecting-rod so jointed to said piston and crank that the line of motion upon the down or working stroke will be substantially perpendicular to said crank in its horizontal position, as and for the purpose described. 100

6. In a single-acting engine, the combination of a piston, a crank, and a connecting-rod jointed eccentrically to the piston in such 105 manner that its line of motion on the down-stroke will be substantially perpendicular to such crank in its horizontal position.

7. In a single-acting engine, the combination of a piston, a crank, and a connecting-rod extending from the crank-pin to a wrist-pin on the under side of said piston and to one side of the center thereof, whereby the line of motion of the connecting-rod on its downstroke will be substantially perpendicular to the crank in its horizontal position, as and for the purpose described. 115

8. In a direct-acting engine, a piston eccentrically jointed to its connecting-rod and the upper face of which is inclined to the line of 120 its movement, as and for the purpose described.

9. In a single-acting engine, the combination of a cylinder, a piston, a crank, and a connecting-rod jointed eccentrically to said piston, the upper face of said piston being inclined to the line of pressure, as and for the 125 purpose described.

10. The combination, with the moving parts of a steam-engine, of a hollow connecting-rod, 130 a crank case or vat containing a lubricating liquid, into which such connecting-rod dips, whereby such lubricant is introduced into the interior of such connecting-rod, and means for

maintaining the level of the lubricating liquid in such vat, and a float in such vat controlling valves for admission of water and escape of the mixture, as and for the purpose described.

11. The combination, with the moving parts of a steam-engine, of a hollow connecting-rod provided at its lower end with a valved opening, a vat of lubricating material into which such connecting-rod dips at each revolution, whereby such lubricating fluid is forced up through said connecting-rod to the upper joint, and means for maintaining the level of the lubricating liquid in such vat, and a float in such vat controlling valves for admission of water and escape of the mixture, as and for the purpose described.

12. In a single-acting engine, the combination of a crank-case containing a lubricating mixture, an open-ended cylinder thereon, a piston, a crank-shaft and crank, a hollow connecting-rod dipping into such mixture at each revolution of the crank, whereby the lubricating material enters such connecting-rod, and means for maintaining the level of the lubricating liquid in such vat, and a float in such vat controlling valves for admission of water and escape of the mixture, as and for the purpose described.

13. In a single-acting engine, the combination of a crank-case containing a lubricating mixture, an open-ended cylinder thereon, a piston, a crank-shaft and crank, a hollow connecting-rod provided at its lower end with a valved opening, whereby the lubricating mixture is forced up through such connecting-rod, and means for maintaining the level of the lubricating liquid in such vat, and a float in such vat controlling valves for admission of water and escape of the mixture, as and for the purpose described.

14. In a single-acting engine, the combination, with the working parts thereof, of a crank-case containing a lubricating mixture, a float therein, a valve for the escape of the mixture, a valve for the admission of water, and means whereby these valves are automatically controlled by said float, as and for the purpose described.

15. In a single-acting engine, the combina-

tion, with the working parts thereof, of a crank-case containing a lubricating mixture, a float therein, a valve for the escape of the water, and a valve for the admission of water, and bell-crank levers controlling said valves and actuated by said float, as and for the purpose described.

16. In a single-acting engine, the combination of two cylinders provided with annular steam-chambers, a steam-chest common to said cylinders and provided with suitable entrance and exit ports, and an exhaust-chamber at one end communicating with the annular steam-chambers of said cylinders, as and for the purpose described.

17. In a single-acting engine, the combination of two cylinders provided with annular steam-chambers, a steam-chest common to said cylinders and surrounded by an annular steam-chamber and provided with an exhaust-chamber at one end communicating with the annular-chamber of the steam chest and the annular-chambers of the cylinders, as and for the purpose described.

18. In a single-acting engine, the combination, with a crank case or vat, of two cylinders located thereon and opening therein, a steam-chest located between said cylinders, annular steam-chambers surrounding said cylinders and said steam-chest, and an exhaust-chamber at one end of said steam-chest communicating with said annular chambers and closed on the end adjoining the crank-case by a stationary head, as and for the purpose described.

19. The combination, with a crank-shaft provided with tapered bearing-surfaces, of correspondingly-tapered bearingssurrounding such surfaces and screwing into a bracket, 5, inclosing-capsattached to the end of said bracket, and retaining-screws passing through said bracket, as and for the purpose set forth.

Signed at Philadelphia, in the county of Philadelphia and State of Pennsylvania, this 25th day of August, A. D. 1886.
